UNITED STATES PATENT OFFICE.

JOSEPH H. KELLEY, OF WEST LAKE, LOUISIANA.

HOSE-CO尤PLING.

1,284,358.

Specification of Letters Patent. Patented Nov. 12, 1918.

Application filed December 3, 1917. Serial No. 205,183.

To all whom it may concern:

Be it known that I, JOSEPH H. KELLEY, a citizen of the United States, residing at West Lake, in the parish of Calcasieu and State 5 of Louisiana, have invented a new and useful Hose-Coupling, of which the following is a specification.

One object of the present invention is to improve the latch mechanism whereby the 10 constituent members of the hose coupling are held together.

Another object of the invention is to provide, in one of the members of the coupling, an element which serves as an abutment for 15 the hose, as an abutment for the gasket, and as a place of mounting for the securing element which holds the latch.

A further object of the invention is to provide novel means for protecting the head 20 of the latch and for protecting the securing element which holds the latch in place.

It is within the province of the disclosure to improve generally and to enhance the utility of devices of that type hereinafter 25 described.

The drawings show a typical embodiment merely, and changes falling within the skill of a mechanic may be made, within the scope of what is claimed, without departing from 30 the spirit of the invention.

In the accompanying drawings:

Figure 1 shows in side elevation a hose coupling constructed in accordance with the present invention;

Fig. 2 is a longitudinal section of the coupling, wherein parts appear in elevation;

Fig. 3 is a cross section taken on the line 3-3 of Fig. 2; and

Figs. 4 and 5 are cross sections taken 40 through the complementary member of the coupling and showing the cam, a part of the latch being disposed in operative relation thereto.

In carrying out the present invention, 45 there is provided a main tubular member 1, equipped in its interior and intermediate its ends with an annular shoulder 2. In front of the shoulder 2, a circumscribing groove 3 is fashioned in the main member. A resilient 50 gasket 4 is mounted in the groove 3 and abuts against one face of the shoulder 2. In its interior, and to the rear of the shoulder 2 the main member 1 is supplied with circumferential ridges 5 which serve to retain 55 a hose 6, within which is located an expander 7 of any desired kind, constituting

means for maintaining the hose 6 engaged with the ridges 5. The hose 6 and the expander 7 abut against the shoulder 2 as clearly shown in Fig. 2 of the drawings. 60 The outer end of the main member 1 is provided with an external annular bead 8. Outstanding parallel ribs 9 are disposed longitudinally of the main member 1, and merge into the bead 8. Resilient tongues 10 lie between the ribs 9, the rear ends of the tongues being attached to the main member 1 by means of securing devices 11. It is to be observed that the securing devices 11 enter the annular shoulders 2, as shown in Fig. 2. 70 These shoulders 2, therefore, reinforce the main member 1 to receive the securing devices 11. Further, the outer ends or heads of the securing devices 11 are housed between the ribs 9 and lie in front of the bead 8, the outer ends of the securing devices being protected in this way, so that the securing devices will not be likely to become detached due to the rough usage to which structures of this class are commonly subjected. 80 The inner ends of the spring tongues 10 provided with heads 14 which may be held on the tongues by securing elements 22, although a skilled mechanic will understand that the heads may be formed integrally with the 85 spring tongues if desired.

The numeral 12 designates a complementary member having a reduced tubular end 16 received within the main member 1 and abutting against the gasket 4. The outer end of the complementary member 12 is provided externally with an annular bead 15 which serves as a protection for the head-carrying end of the tongue 10 when the main and complementary members are locked together, as shown in Fig. 2. The complementary member 12 is supplied with an internal annular shoulder 17 and in the bore of the complementary member, outwardly of the shoulder 17, annular ridges 18 are fashioned, these ridges serving to retain a hose 19 held in place by an expander 20, the hose and the expander abutting against the shoulder 17. 100

A salient feature of the invention remains 105 yet to be discussed. It is to be noted that in the outer surface of the complementary member 12, transverse notches 21 are formed, these notches defining shoulders 23, wherewith the heads 14 of the latch tongues 120 10 engage, to hold the main and complementary members of the coupling together,

The rear walls 24 of the notches 21 are curved at their ends, and merge into the outer surface of the complementary member 12, to define cams 25. The constituent members 1 and 12 of the coupling may be telescoped by a right line movement, the tongues 10 yielding and permitting the heads 14 to engage with the shoulders 23. When it is desired to separate the members 1 and 12 of the coupling, relative rotation therebetween may be produced, whereupon the heads 14 of the latch tongues 10 will ride first on to the cams 25 and thence on to the outer surface of the complementary member 12, it being unnecessary to pry the heads 14 out of the notches 21 when it is desired to separate the parts of the coupling. Since the tongues 10 move between the ribs 9, a single securing element 11 may be employed for holding each tongue in place and the tongues will not swing on these securing elements.

The tongues 10 are supplied at their inner ends with hooked portions 51 which engage the tubular member 1 and remove a large amount of strain from the securing devices 11. The outer ends of the tongues 10 are hooked as shown at 50 to engage with the heads 14, the strength of the structure being correspondingly enhanced.

Having thus described the invention, what is claimed is:

1. A hose coupling comprising coöperating tubular members each provided with means for holding a hose section fixed thereto; and a spring tongue secured to one member and provided with a head, the other member having a transverse notch extended

part way there-around, the notch defining a shoulder with which the head engages to hold said members together, the rear wall of the notch merging into the outer face of said other member to form cams which disengage the head from the shoulder upon relative rotation between said members.

2. A hose coupling comprising a main member having longitudinal ribs and a terminal annular bead united with the outer ends of the ribs; a spring tongue disposed between the ribs and having a head at its inner end; a securing device uniting the outer end of the tongue with the main member and housed between the ribs in front of the bead; a complementary member fitting within the main member and having a transverse notch defining a shoulder wherewith the bead engages to hold said members together, the rear wall of the notch being curved at its ends, and merging into the outer face of the complementary member to form cams which disengage the head from the shoulder and direct the head upon the outer face of the complementary member when relative rotation between said members is brought about, the complementary member having an annular terminal bead forming a guard for the head when the head is engaged with the shoulder.

In testimony that I claim the foregoing as my own, I have hereto affixed my signature in the presence of two witnesses.

JOSEPH H. KELLEY.
